Primary Examiner—A. Hugo Word
Assistant Examiner—Lavone D. Tabor
Attorney, Agent, or Firm—Richard C. Litman[57] **CLAIM**

The ornamental design for a combination tomahawk and broom handle, as shown and described.

DESCRIPTION

FIG. 1 is an environmental perspective view of a combination tomahawk and broom handle showing my new design; FIG. 2 is a front elevational view thereof; FIG. 3 is a rear elevational view thereof; FIG. 4 is a right side elevational view with the left side being a mirror image thereof; FIG. 5 is a top view thereof; and, FIG. 6 is a bottom view thereof.

The broken line showing of a hand in FIG. 1, lettering and geometric designs in FIGS. 1 and 4, and a broom head in FIGS. 1-4 is for illustrative purposes only and forms no part of the claimed design.
